UNITED STATES PATENT OFFICE

121,970

DESIGN FOR A LOCKING CAP FOR GASOLINE TANK

Solomon Wise, Shaker Heights, Ohio

Application July 28, 1938, Serial No. 78,795

Term of patent 14 years

To all whom it may concern:

Be it known that I, Solomon Wise, a citizen of the United States, residing at Shaker Heights, in the county of Cuyahoga and State of Ohio, have invented a new, original, and ornamental Design for a Locking Cap for Gasoline Tank, of which the following is a specification, reference being had to the accompanying drawing, forming part thereof.

In the drawing, the figure is a perspective view of a locking cap for a gasoline tank showing my new design.

I claim:

The ornamental design for a locking cap for gasoline tank, as shown.

SOLOMON WISE.
